UNITED STATES PATENT OFFICE.

GEORGE ALGER PENNOCK AND WILLIAM E. JOHNSON, OF ROCK ISLAND, ILLINOIS, ASSIGNORS TO ROCK ISLAND PLOW COMPANY, OF ROCK ISLAND, ILLINOIS, A CORPORATION OF ILLINOIS.

FOOT-LIFT FOR SULKY-PLOWS.

No. 830,000.

Specification of Letters Patent.

Patented Sept. 4, 1906.

Application filed July 24, 1903. Serial No. 166,810.

To all whom it may concern:

Be it known that we, GEORGE ALGER PENNOCK and WILLIAM E. JOHNSON, citizens of the United States of America, and residents 5 of Rock Island, Rock Island county, Illinois, have invented a certain new and useful Improvement in Foot-Lifts for Sulky-Plows, of which the following is a specification.

Our invention contemplates an improved 10 foot-lift for use in connection with sulky-plows of various constructions.

It is adapted more particularly for use in connection with sulky-plows of that type in which provision is made for adjusting or controlling 15 the landside-wheel independently of the balance of the machine.

Generally stated, the object of our invention is to provide a simple, improved, and highly-efficient foot-lift.

20 A special object is to provide an improved foot-lift so constructed and arranged that the foot-lever will remain in a horizontal or practically horizontal position from the time the foot is placed upon it until the landside-wheel assumes the desired position relatively 25 to the balance of the machine.

Another object is to provide an improved construction and arrangement whereby a parallel motion may be utilized in a practical 30 and efficient manner for maintaining the foot-lever in the said horizontal or practically horizontal position during the independent manipulation of the landside-wheel.

It is also an object to provide certain details and features of improvement tending to 35 increase the general efficiency and serviceability of a foot-lift arrangement of this particular character.

To the foregoing and other useful ends our 40 invention consists in matters hereinafter set forth and claimed.

In the accompanying drawings, Figure 1 is a side elevation of a sulky-plow equipped 45 with a foot-lift arrangement embodying the principles of our invention, the plow being shown in working position relatively to the wheels. Fig. 2 is a plan of the plow shown in Fig. 1. Fig. 3 is a view similar to Fig. 1, but showing the plow raised out of the furrow. 50 Fig. 4 is a detail sectional view of the connection between the crank-shaft and spindle of

the landside-wheel. Fig. 5 is a detail cross-section on line 5 5 in Fig. 4.

The plow with the exception of the foot-lift arrangement can be of any suitable known or approved construction. For example, as illustrated, it may comprise a plow-beam A and a plow B of the usual form and construction. The plow and beam can be supported by front and rear furrow-wheels C 60 and D and by a landside-wheel E. The front furrow-wheel can be mounted on the out-turned lower portion of a vertically-arranged stem c, which is adapted to turn in a bracket-bearing c', secured to the plow-beam. This 65 bracket bearing or sleeve is adapted to slide up and down upon the said stem. The tongue c² is preferably secured to the upper end of the stem c. As a means for raising and lowering the sleeve c' upon the said stem 70 so as to raise and lower the plow the machine can be provided with a hand-lever F, which is secured at its lower end to the horizontally-arranged crank-shaft G and which is connected with the sleeve c' through the medium of a link f and a rock-shaft f'. The 75 said rock-shaft is provided with two arms f² and f³, the former having its free end connected with the said link f and the latter being connected with the upper end of the stem c through the medium of a link f⁴ and a casting f⁵. It is through the medium of this casting f⁵, having a hinge-joint x with the tongue, that the latter is connected with the stem c. Thus when the said lever is swung about its 80 axis it causes a rocking motion of the rock-shaft f' and a consequent vertical sliding movement of the sleeve c' upon the stem c. This of course carries the forward end of the 85 said beam up or down, according to the direction in which the lever is swung. The rear furrow-wheel D is preferably in the nature of a caster-wheel. As such it is mounted upon the rearwardly-extending lower portion of a 90 caster-stem d, which latter is mounted to turn or oscillate in a bearing-sleeve d'. In order that the rear portion of the plow-beam and the plow may rise and fall relatively to this rear furrow-wheel or caster-wheel, the 95 said sleeve d' is preferably connected with the said plow-beam by means of upper and lower links d² and d³, said links having their 100

forward ends pivotally connected with the plow-beam and their rear ends pivotally connected with ears on the sleeve d' . One of the upper of said links is preferably of the nature 5 of a bell-crank, being provided with a rear downwardly-extending arm d^4 . This arm is connected, by means of a link d^5 , with a stub-arm d^6 on the lower end or hub portion of the said hand-lever. In this way the said lever 10 when swung about its axis will cause the said bell-crank to either lift or lower the plow relatively to the rear furrow-wheel, according to the direction in which it is swung. When the said lever F is pulled back and toward the 15 driver's seat H , the plow will be lifted bodily relatively to the front and rear furrow-wheels. It will be observed at this junction that the said seat is mounted upon the sleeve d' , and hence that the weight of the driver is 20 suitably sustained by the rear furrow-wheel. In order that the tongue c^2 may exert a certain amount of control over the rear furrow-wheel as well as the front furrow-wheel, the casting f^6 is preferably provided with a horizontally and traversely extending slot f^6 , 25 adapted to receive the upturned forward end of a rod f^7 , the latter having its rear end suitably connected with a laterally-disposed crank-arm d^7 on the upper end of the stem d . 30 Thus the tongue holds the stem d against turning or oscillating in its bearing while the machine is running straight ahead, but allows the said stem to turn and permit the rear furrow-wheel to swing freely from side to side 35 when the course of the machine is altered—as, for example, in turning around.

The landside-wheel E is preferably mounted on a spindle e , the latter being mounted at the end of a casting or crank-arm e' . This 40 casting or crank-arm is loosely mounted on the crank-shaft G , which latter is mounted to turn in a bearing g , secured to the plow-beam. The hand-lever e^2 is preferably rigidly secured to or made an integral part of 45 the casting or crank-arm e' . The toothed rack e^3 is adapted to be engaged by the locking-bolt e^4 on the said hand-lever e^2 and is rigidly secured to the said shaft G . Thus when the said hand-lever and rack are locked 50 together the crank-arm e' is locked against turning relatively to the shaft G ; but by disengaging the said lever from its rack the spindle e , upon which the landside-wheel is mounted, can then be utilized as a fulcrum 55 about which to swing the lifting-lever composed of the rigidly-connected arm e' and lever e^2 . A backward pull on this lever will obviously lift the crank-shaft and plow-beam, or, in other words, cause a relative down- 60 ward swing on the part of the spindle e about the crank-shaft as an axis. In other words, the landside-wheel can be given an independent manipulation by simply pulling back on the lever e^2 after the same has been disengaged from the rack e^3 . It is also obvious

that all three wheels can be simultaneously controlled or adjusted relatively to the plow and beam by disengaging the lever F from its rack f^8 and by then rocking the crank-shaft G in its bearings.

In order that the driver may use his foot for assisting in lifting the plow out of the furrow, a foot-lever I is preferably mounted upon the said spindle e , so as to turn freely thereon, and is provided with a downwardly-extending arm i . Thus formed the said foot-lever is in the nature of a bell-crank having a rear portion i' , upon which the driver may conveniently place his foot to assist in raising the plow out of the furrow. In order that the said foot-lever may serve in the capacity of a lever with the spindle e as a fulcrum, its arm i is preferably connected with the lower arm Z of the rack e^3 by means of a link i^2 . It will be seen that the distance from the center or axis of the said spindle to the center or axis of the shaft G is the same as the distance between the points of pivotal connection of the opposite ends of the link i^2 with the arm i and the lower end of the rack e^3 . Thus the 80 link i^2 and the casting or crank-arm e' are adapted to constitute the at-all-times parallel members of a parallel-motion connection between the landside-wheel and the plow-beam. In other words, the members i^2 and e' constitute the horizontally-disposed elements of what may be termed a "parallel-motion" connection, and the members i and Z constitute the vertically-disposed elements 85 of said connection. With this arrangement 90 the lever F when released from its rack can be pulled back so as to raise the plow and beam, and the driver can employ his foot for assisting in this operation by bearing down on the rear end of the lever I . In other 95 words, the spindle e will act as a fulcrum about which to tilt a lever, the long end of the lever being adapted to be grasped by the hand, while its short end is adapted to be engaged by the foot of the driver; but when the 100 plow is in working position and it becomes necessary or desirable to wing the plow—that is to say, to keep the bottom level while working on a side hill, for example, or while the landside-wheel is running over an obstruction—then the landside-wheel can be 105 controlled independently of the balance of the machine by manipulating the lever e^2 , and the advantage of the parallel-motion connection lies in the fact that while thus 110 manipulating the landside-wheel independently of the balance of the machine the foot-lever I will retain its horizontal or practically horizontal position from the time the driver starts to move the lever e^2 until the plow is 115 given the desired position. This, of course, and as will be clearly understood is due to the action of the parallel motion, the connection causing the arm i to remain parallel 120 with the arm Z on the bottom of the rack. In 125 130

other words, the foot-lever will maintain its horizontal position as long as the position of the rack e^3 remains unchanged. This is of great advantage in a foot-lift of this character, as it enables the driver to advantageously and conveniently employ his foot for assisting in manipulating the landside-wheel relatively to the plow and beam. For when the landside-lever is manipulated for the purpose 5 of rocking the plow or lifting up or winging, which is usually accomplished by throwing the lever either forward or backward, as the case may be, this parallel-motion connection maintains the foot-lever in its horizontal or 10 practically horizontal position. When the plow is raised from the ground, which is accomplished by pulling back on the lever F, the foot-lever then, of course, swings in a downward direction, the parallel-motion 15 connection, the crank-arm, and the crank-shaft at such time being maintained in a rigid condition and having no movement whatever relatively to each other. The parallel-motion connection makes it possible to 20 manipulate the landside-lever without effecting the availability of the foot-lever as a means for assisting the lever F in raising the plow from the ground. No matter what is done 25 to the landside-wheel independently of the balance of the machine it will be seen that 30 the foot-lever is always ready and in proper position to be engaged by the driver's foot.

What we claim as our invention is—

1. In a sulky-plow, the combination of a 35 plow and beam, supporting-wheels including a landside-wheel, a hand-lever connected and arranged for adjusting said landside-wheel relatively to the plow and beam, a rearwardly-projecting foot-lever for assisting 40 said hand-lever in its work, means whereby the landside-wheel may also be adjusted relatively to and independently of the other wheels, and a parallel-motion connection adapted to maintain the said foot-lever in its 45 horizontal position during the operation of adjusting the landside-wheel relatively to the plow and beam and independently of the other wheels.

2. In a sulky-plow, the combination of a 50 plow and beam, supporting-wheels including a landside-wheel, a hand-lever connected and arranged for adjusting said landside-wheel relatively to the plow and beam, a rearwardly-projecting foot-lever for assisting 55 said hand-lever in its work, means whereby the landside-wheel may also be adjusted relatively to and independently of the other wheels, and a parallel-motion connection for maintaining said foot-lever in its horizontal 60 position during the operation of adjusting the landside-wheel relatively to the plow and beam and independently of the other wheels, said parallel-motion connection including a member adapted to remain sta-

tionary relatively to the plow-beam during 65 the independent adjustment of the wheel.

3. In a sulky-plow, the combination of a plow and beam, supporting-wheels including a landside-wheel, a rearwardly-projecting foot-lever for adjusting said landside-wheel 70 relatively to the plow and beam, means whereby the landside-wheel may also be adjusted relatively to and independently of the other wheels, and a parallel-motion connection for maintaining said lever in its horizontal 75 position during the operation of adjusting the landside-wheel relatively to the plow and beam and independently of the other wheels.

4. In a sulky-plow, the combination of a 80 plow and beam, supporting-wheels including a landside-wheel, a rearwardly-projecting foot-lever for adjusting said landside-wheel relatively to the plow and beam, means whereby the landside-wheel may also be ad- 85 justed relatively to and independently of the other wheels, and a parallel-motion connection for maintaining said lever in its horizontal position during the operation of adjusting the landside-wheel relatively to the plow and 90 beam, said parallel-motion connection including a member adapted to remain stationary relatively to the plow-beam during the relative adjustment of the wheel.

5. In a sulky-plow, the combination of a 95 plow and beam, supporting-wheels includ- 100 ing a landside-wheel, a transversely-dis- posed shaft, a crank-arm having a hub por- tion loosely mounted on said shaft, a spindle carried by the said crank-arm and upon 105 which the said landside-wheel is mounted, a hand-lever rigid with the hub portion of said crank-arm, a rack rigidly mounted upon said shaft and provided with a depending arm, a locking-bolt on said lever adapted to engage 110 said rack, a bell-crank-shaped foot-lever mounted on said spindle, and a link connect- 115 ing said depending arm of the rack with the said foot-lever, whereby the said foot-lever is adapted to retain its horizontal position 120 when the said hand-lever is disengaged from the said rack and the crank-arm swung about the said shaft.

6. In a sulky-plow, the combination of a 115 plow and beam, supporting-wheels shift- 120 ingly connected with said beam, a foot-lift for raising and lowering the plow, means whereby the plow may be winged, and a parallel-motion connection for maintaining said lift in its horizontal position during the oper- 125 ation of winging the plow the point of pivotal connection between two elements of said connection being coincident with the axis of one of said wheels.

7. In a sulky-plow, the combination of 125 supporting-wheels, a plow suitably carried by said wheels and adapted to be raised and lowered, a foot-lift for raising and lowering

the plow, means whereby the plow may be winged, and a parallel-motion connection for preventing tilting movement of the lift when the plow is winged.

- 5 8. In a sulky-plow, the combination of supporting-wheels, a plow suitably carried by said wheels and adapted to be raised and lowered, a hand-lever suitably connected for raising and lowering the plow, a foot-lift for
10 assisting said hand-lever in its work, means whereby the plow may be winged at will and a parallel-motion connection for preventing

tilting movement of the lift when the plow is winged the point of pivotal connection between two elements of said connection being 15 coincident with the axis of one of said wheels.

Signed by us at Rock Island, Illinois, this 7th day of July, 1903.
